UNITED STATES PATENT OFFICE.

FRANK H. MOONEY, OF HINSDALE, ILLINOIS, ASSIGNOR TO CLARENCE E. BARRETT,
OF CHICAGO, ILLINOIS.

END-FACE GRINDER.

1,393,956.

Specification of Letters Patent.

Patented Oct. 18, 1921.

Application filed September 18, 1920. Serial No. 411,091.

To all whom it may concern:

Be it known that I, FRANK H. MOONEY, citizen of the United States, residing at Hinsdale, in the county of Du Page and State of Illinois, have invented certain new and useful Improvements in an End-Face Grinder; and I do hereby declare the following to be a full, clear, and exact description of the invention, such as will enable others skilled in the art to which it appertains to make and use the same.

My invention relates to grinding machines and in its general objects aims to provide an easily manipulated and widely adaptable machine for surfacing the ends of tubes, rods or barrels while maintaining a given spacing from the surfaced end and some other portion of the object which is being ground. Furthermore, my invention aims to provide a machine of this class so arranged as to hold one after another of the objects which are to be ground in proper position for the grinding, to feed the same automatically and with a predetermined pressure past the grinding surface, and then to carry these objects into positions where they can be removed either by hand or by gravity.

In one of its more particular aspects, my invention relates to the grinding of tubes or rods to predetermined lengths and for this purpose aims to provide simple and easily fed means for carrying the tubes or rods through the field of the grinding and for thereafter releasing them so that they will drop out of the clamps by gravity. In this aspect, my invention also aims to provide simple and single means for effecting the clamping of the objects while these are being carried into position and past the grinding surface, to provide a simple arrangement of clamping means, and to provide simple means for adjusting the length to which the objects are to be ground.

In another aspect, my invention aims to provide simple means adapted either for grinding tubes to predetermined lengths or for grinding the closed ends of barrels or the like to a predetermined thickness, and in this embodiment also aims to provide simple means for adjusting the resulting lengths or thicknesses and for adapting the machine to tubes or barrels of varying diameters. Furthermore, my invention aims to provide a grinding machine which will readily permit a single grinding disk to be

effectively used in connection with tubes, barrels or rods fed to the machine by a plurality of operators, and in which the same grinding disk can be used simultaneously for grinding objects to different lengths. 60 Still further and more detailed objects will appear from the following specification and from the accompanying drawings, in which—

Figure 1 is an elevation of a machine embodying my invention.

Fig. 2 is a plan view of the same.

Fig. 3 is a reduced plan view of the cam plate associated with the tube feeding mechanism at the left hand of Fig. 1. 70

Fig. 4 is a reduced plan view of the spindle-raising cam used in connection with the barrel or tube feeding drum at the right hand of Fig. 1.

Fig. 5 is an enlarged and fragmentary 75 plan view of the tube-feeding drum of Fig. 2, showing the clamping arrangement.

Fig. 6 is a vertical section through the same parts, taken radially of the drum along the correspondingly numbered line in Fig. 5. 80

Fig. 7 is an enlarged and fragmentary longitudinal section through the top of one of the spindles at the right hand of Figs. 1 and 2, and through a closed-end barrel supported by the same, showing the arrangement used in grinding the closed end 85 of a barrel to a predetermined thickness.

In the embodiment of the drawings, the machine of my invention includes a base 1 supporting three vertical risers 2, 4 and 5, 90 each of which risers has its upper portion reduced in diameter to afford a stationary shaft for one of the main rotating members of the machine. The middle riser 2 has a shoulder adjacent to its juncture with the shaft 3 carried by the same, which shoulder forms a thrust bearing for the hollow hub 6 of a pulley 7 driven by a belt 8 and which hub is also fast upon a metal disk 9 having a sheet of an abrasive material 10 glued to 100 its lower face.

The riser 4 likewise has a shoulder at its juncture with the shaft 11 carried by the same, which shoulder supports the hub 12 of a drum 13 provided on its periphery with 105 a series of vertical notches, the risers 2 and 4 being so spaced that the drum 13 underhangs a portion of the disk 9. Each of these notches preferably has its forward face 14 (when considered as to the direction in which 110

the drum normally revolves) at an acute angle to the periphery of the drum and its rear face 15 substantially radial of the drum, so that this rear face will exert a direct thrust 5 on an object inserted in the slot, such as the tube 11 of Fig. 5.

To hold the objects in the slots, I provide suitable clamping means, such as hinges, each consisting of a base plate 8 fastened to the 10 periphery of the drum and a clamping plate 19 swiveled to the base plate and adapted to swing toward or away from the drum. I also provide suitable means for automatically closing each clamp as it approaches the field 15 of the grinding, for holding the clamp tightly closed while it carries the stock through the field of the grinding operation, and for automatically releasing the clamping pressure after this part of the drum has 20 passed out of the grinding field. For this purpose, I desirably employ the same belt 20 which slowly rotates the drum 13 during the operation on the machine, by simply passing this belt peripherally of the drum outside 25 of the clamping belts 19, the belt being kept from slipping downward off the clamping plates by its engagement with pins 21 carried by the drum and each extending through a slightly larger perforation in the adjacent 30 clamping plate 19 as shown in Fig. 5, and I desirably use these same pins 21 also for limiting the outward swinging of the said clamping plates. To take the thrust of the 35 grinding and to insure a grinding of each object to the desired length, I mount a cam plate 22 on the riser 4 below the drum 13. This plate desirably consists of a disk having the main part of its upper surface spaced from the abrasive disk 10 by a distance 40 greater than the length to which the objects 11 are to be ground. This disk has on the edge directed toward the middle riser 2 an arcuate cam rim 22 which gradually slopes upward from its beginning at the bottom of 45 Fig. 3 and which extends horizontally under a portion of the disk 9, and the disk desirably has a peripheral portion cut away at the side opposite that on which the cam 23 is mounted, as also shown in Fig. 3.

50 In using the machine as above described for grinding tubes, each of these tubes is slipped into one of the slots back of a clamping plate 19 when the latter is approximately in the position of the tube 11^A of Fig. 2, or 55 just before the adjacent clamping plate is engaged by the belt 20. When thus inserted, the lower end of the tube rests loosely on the horizontal flange of the disk 22 and the top of the tube is below the plane of the abrasive 60 disk 10. As the drum 13 revolves, the belt 20 clamps the plate 19 against the tube with a pressure just sufficient to hold the tube vertical, while still permitting it to be slid upward by the cam 23, after which the tube 65 rides up on the top of this cam as shown at

11^B or with its own top in engagement with the abrasive disk 10. When carried still further around to the position of the tube 11^C in Fig. 2, the adjacent clamping plate 19 clears the belt 20, thus releasing the pressure 70 and permitting the centrifugal force due to the rotation of the drum to swing the clamping plate outward or away from the adjacent groove, so that the tube can drop by gravity past the recessed edge of the disk 75 22 into a suitable hopper which is not shown on the drawings.

In practice, the tension of the belt is easily adjusted to secure the desired tightness of the clamping and it will be noted that this 80 clamping increases as the tubes are raised and is maintained at its maximum during the grinding, thereby insuring a square facing of the end of the tube. The disk 22 and the cam 23 on the latter can readily be adjusted 85 as to their height by loosening a set screw 24 which clamps this disk adjustably to the riser 4, so that I can readily vary the length to which the tubes, rods or the like are to be ground. 90

While the arrangement as above described is highly satisfactory for many purposes, it is limited in scope to such diameters or rods, tubes or barrels as can readily be gripped in the slots of the drum, and to grinding objects 95 to a predetermined total length. It does not lend itself readily for use with objects of a smaller diameter than that for which the peripheral clots in the drum 13 are designed, nor for grinding the closed ends of barrels 100 to a predetermined thickness. For these latter purposes, I preferably provide a different arrangement for holding the stock which is to be ground, and desirably provide stock holders which will be moved bodily 105 with the stock itself when the latter is being raised into the grinding position.

To adapt my machine for such cases also, I desirably provide a second drum 25 pivoted on a shaft 26 which forms an extension 110 for the riser 5 and which drum has a hub bearing against a shoulder at the juncture of the stationary shaft 26 with the riser 5, as shown at the right hand of Fig. 1. The drum 25 desirably has a pair of peripheral 115 beads 27 spaced vertically from each other to afford guides for a belt 28 by means of which this drum is slowly rotated, the belts 8, 20 and 28 being all driven from a single source of power not shown in the drawings. 120 The risers 2 and 5 are so spaced that the drum 25 underhangs a considerable portion of the grinding disk 9, and the drum 25 has near its periphery a plurality of bores extending longitudinally of the drum and desirably parallel to its axis. Each of these bores slidably houses the shank of a spindle 28 which rests by gravity at its lower end against a disk 29 secured to the riser 5 by a set screw 30. This disk has fast upon it a 130

substantially arcuate cam 31 which includes a pair of inclined portions connected by a horizontal portion which extends along the edge of the disk nearest to the riser 2. Thus 5 arranged, it will be obvious from Fig. 1 that as the drum 25 is rotated, each spindle will be lifted by this cam as it approaches the grinding disk, then will be moved horizontally under this disk, and afterward re- 10 turned by gravity to its original position as shown at the extreme right hand of Fig. 1. Consequently, any stock carried by the spindles will be raised into the grinding position and held against the abrasive disk during a 15 part of its revolution around the axis of the drum.

Where this portion of my machine is to be used in grinding hollow objects to predetermined lengths, I provide each of the spindles 20 with a shoulder 31 upon which the lower end of the stock will rest and through which the thrust of the grinding is then transmitted to the cam 31. By using spindles having their upper or reduced shanks of varying diameters, I can readily adapt this portion of my machine for grinding tubular objects of various bores, including sizes which could not be handled in the other part of my machine when this is adapted for gripping 25 low objects of much larger diameter. For grinding the ends of barrels or the like to predetermined thicknesses, I select spindles having their reduced upper stem portions shorter than the bore of such barrels, so that 30 the lower end of the barrel will not engage the shoulder 31, but the thrust of the grinding will be transmitted through the tip of the spindle. In this manner, as shown in Fig. 9, I can readily grind the closed end of 35 a barrel 32 to a predetermined thickness. This thickness can be varied by loosening the set screw 30 and raising or lowering the cam-carrying disk 29, and the same adjustment of the disk can likewise be used for 40 varying the effective distance between the shoulders 31 on the spindles and the grinding disk, so as to adapt this part of my machine for grinding tubular objects to varying 45 total lengths.

50 With the twin drum arrangement of grinding machine as above described, it will be obvious that the same machine can be used for grinding objects varying widely in shape and size, and that both parts of the 55 machine can be employed simultaneously by two different operators, or with slowly revolving drums even by one and the same operator using both hands in feeding the stock to the machine and using one hand also in 60 removing the finished stock from the right hand portion of the machine. My duplex machine therefore saves considerable space, power, first cost, and cost of attendance over 65 two separate machines for the same class of work, while also affording adjustments

which adapt it for use in the end grinding of objects varying greatly in size and shape. However, while I have illustrated and described the clamping drum part of my machine as used in connection with tubes, and 70 have shown the clamping plates as swiveled to hinge plates fastened to the periphery of one of the drums, I do not wish to be limited to the particular form of stock illustrated, nor to the above mentioned or other details 75 of the construction and arrangement here disclosed. Obviously, various additions, omissions or other changes might be made without departing from the spirit of my invention or from the scope of the appended 80 claims.

I claim as my invention:

1. In a grinder, a grinding disk having a downwardly directed abrasive face, a rotating drum having a vertical axis and partially underhanging the said disk, the drum having on its periphery a plurality of grooves extending longitudinally of the drum and each adapted to receive one of the objects which are to be ground, separate 85 clamping means carried by the drum and respectively arranged for retaining the objects in the grooves, single means for actuating each of the clamping means while approaching and passing under the said disk, 90 and means for forcing the objects upwardly 95 against the disk while under the latter.

2. In a grinder, a grinding disk having a downwardly directed abrasive face, a rotating drum having a vertical axis and partially underhanging the said disk, the drum having on its periphery a plurality of grooves extending longitudinally of the drum and each adapted to receive one of the objects which are to be ground, separate 100 clamping means carried by the drum and respectively arranged for clamping the objects against the drum to retain the objects in the grooves, means for actuating the clamping means while approaching and passing under the said disk, and stationary 105 cam means for raising the objects into contact with the disk while passing under the latter.

3. A grinder as per claim 1, in which 110 the clamping means include movable stock clamping elements associated with the respective grooves, and a single flexible member arranged for actuating all of the clamping elements.

4. A grinder as per claim 1, in which the clamping means include movable stock clamping elements associated with the respective grooves, and a belt arranged for 115 rotating the drum and for successively actuating the clamping elements.

5. A grinder as per claim 1, in which the clamping means include movable stock clamping elements associated with the respective grooves, and a belt arranged for 120 125 130

rotating the drum and for successively actuating the clamping elements, a belt rotating the drum and successively actuating the clamping elements, and common means for limiting the outward movement of the clamping elements and for retaining the belt in operative position.

6. A work holder for carrying objects to a grinding disk, comprising a rotating drum having on its periphery a plurality of longitudinal grooves, clamping elements movably mounted on the drum and respectively overlapping the grooves, and means for successively moving each clamping element toward the drum to clamp an object in the adjacent groove during a part of the rotation of the drum.

7. A work holder for carrying objects to a grinding disk, comprising a rotating drum having on its periphery a plurality of longitudinal grooves, clamping plates pivoted to the drum respectively adjacent to the grooves and each adapted to be swung away from the adjacent groove by centrifugal action, and means for swinging each plate in-

wardly of the drum and holding it in its inwardly swung position during a part of the rotation of the drum.

8. A work holder for carrying objects to a grinding disk, comprising a rotating drum having on its periphery a plurality of longitudinal grooves, clamping plates pivoted to the drum and respectively overlapping the grooves, and a tensioned flexible member extending around a portion only of the periphery of the drum and engaging a part of the said plates to swing the latter toward the adjacent grooves.

9. A work holder as per claim 8, in combination with common means for limiting the swinging of the plates away from the groove and for retaining the flexible member in operative position.

10. A grinder as per claim 2, in which the cam means are adjustably spaced from the drum, whereby to vary the effective height to which the objects are raised.

Signed at Chicago, Illinois, Sept. 9, 1920.

FRANK H. MOONEY.
